METHOD OF MAKING INDUCTIVE WINDINGS

Lyman G. Ketcham, Brooklyn, N. Y., assignor to
Teleradio Engineering Corporation, New York,
N. Y., a corporation of New York

Application September 12, 1934, Serial No. 743,711

8 Claims. (Cl. 175—359)

This invention relates to improvements in methods of making inductive windings.

Heretofore inductive windings have been made in one unitary section and in order that the inductance of such a winding could be determined with some degree of accuracy, the winding would be provided with a number of turns in excess of what would be expected to be sufficient for the required inductance. The unitary winding could then be checked against a standard by connecting the ends of the wire to a test apparatus and by successively winding off extra turns and making tests until the inductance reached approximately the desired figure. Naturally, such procedure involves considerable cost both in time and material and the inductance could never be determined with more than a fair degree of accuracy.

An object of the invention is to provide improved windings of the maximum accuracy so far as their inductance is concerned.

Another object of the invention is to provide methods for making windings in which the inductance can be accurately determined.

In the practice of the present invention, windings are made in more than one section instead of one section, and initially one section is movable relative to the other section or sections, so that the inductance of the total winding can be accurately determined. For example, a winding may be made in two sections; one section being rigidly fastened to the rod or spool of insulating material upon which the winding is mounted, and the other section being initially movable along such rod or spool. Due to this movement, it is possible to adjust the movable winding relative to the fixed winding until the inductance of the two sections reaches the desired amount, at which time the movable section may be permanently secured to the rod or spool. In order that a winding of this character may be produced the following steps are carried out; the first section is wound directly and permanently onto the rod or spool and then a sheath of thin material is positioned on this rod or spool, and the wire of the first section is then continued and wound into the second section with the sleeve in place. This sheath may totally or partially surround the rod as conditions warrant. When the winding of the second section has been completed, the sheath is removed and due to the space occupied by the sheath, the second section can be moved, within limits, along the rod or spool. The two sections are then compared with a standard inductance and the movable section moved relative to the fixed section until the inductance of the two sec-

tions balances with the fixed standard. When such position has been reached, the initial movable section is permanently secured to the rod or spool by means of some quick drying waterproof lacquer. If desired, the winding may be made in more than two sections, in practice it having been found that under certain conditions a winding of three or four sections or even more will produce admirable results.

Other features, objects and advantages of the invention will become apparent by reference to the following detailed description taken in conjunction with the accompanying drawing illustrating the invention, wherein

Fig. 1 is a vertical section of a winding during the process of manufacture.

Fig. 2 is an end view of the winding during the process of manufacture; and

Fig. 3 is a view similar to Fig. 1 illustrating the division of a winding into more than two sections during manufacture.

Referring now to the drawing and particularly to Figs. 1 and 2, 10 indicates a rod or spool of some suitable insulating material such as wood, fibre, ceramic material, etc., upon which a winding 11 is to be mounted. The wire 11 is shown as being wound into a self-supporting coil 12 after which the wire is further wound into a self-supporting coil 14. The two coils, as indicated, are in series aiding relation. A sheath 15 of thin material is shown as partially surrounding the rod 10 with the coil 14 wound upon the rod and the sleeve.

In constructing the winding in sections, the wire 11 is first wound tightly upon the rod 10 to form the coil 12. As the coil 12 is completed, the turns thereof are locked in place by some suitable quick drying cement, and then the wire 11 is further wound into the coil 14, around the rod 10 and the sheath 15. When this coil has been completed and the turns thereof locked against unwinding, the sleeve 15 is withdrawn. The withdrawal of the sheath 15 necessarily causes the coil 14 to fit somewhat loosely on the rod 10 so that this coil can be moved around and longitudinally of the rod within the limits set up by the length of wire between the two coils 12 and 14.

The two terminals of the two sections of the total winding are then connected to test apparatus for comparison with an inductance of known value. This section 14 is then moved toward or away from the section 12 until the inductance of the two sections matches that of the standard. When this condition has been

reached, the section 14 is locked to the rod 10 by application of some suitable quick-drying non-hygrosopic cement.

If desired, the winding may be made in more than two sections, such a winding being illustrated in Fig. 3 wherein the winding is shown as being made up of sections 20, 21, 22 and 23. In the manufacture of this winding, sections 20, 21 and 22 are wound tightly onto the rod 10' while the section 23 is wound in the same fashion as the section 14, use being made of a sleeve 15'. With this single movable section, the inductance of the entire winding can be accurately determined in the manner set forth hereinbefore.

15 From the foregoing it will be seen that a winding constructed in the manner set forth possesses the advantage that it can be manufactured much more quickly than can windings of single sections manufactured in the manner set forth previously. The cost of manufacturing this improved winding naturally is considerably less than the cost of manufacturing a single section winding according to prior practice. However, in addition to the advantages inherent in this 20 winding so far as accuracy, speed of manufacture and reduction of cost of manufacture, the improved winding of the invention possesses other advantages. For example, if a winding is made in two or more sections, the distributed capacity 25 of the entire winding is materially reduced as compared with a single section winding or similar inductance with accompanying advantages. If the winding is made in two sections the distributed capacity will be cut approximately in 30 half. If the winding is made in three sections, the distributed capacity of the entire winding will reach approximately one-third of the distributed capacity of a single section winding of the same inductance. Another advantage inherent in this 35 40 type of construction resides in the fact that the use thereof in a circuit reduces the effective resistance of the circuit at high frequency. Consequently, the frequency range of a circuit can be materially increased by utilizing a winding embodying the present invention.

When the value of an inductance in certain uses need not be determined as accurately as is made possible by the above described operation, beneficial results will be obtained by utilizing a sectional winding wherein all of the sections are initially permanently secured to the core. The number of turns in each section can be predetermined with sufficient accuracy as to cause the inductance of the complete winding to come within the allowed range. Such a winding possesses proportionate advantages in the reduction of distributed capacity and in the reduction of the effective resistance of the circuit in which the winding is used.

60 From the foregoing it will be seen that improved windings of the invention possess advantages not found in windings heretofore utilized. Furthermore, the method of making the improved windings of this invention serves to materially 65 reduce the time required for making a winding of a desired inductance; reduces the cost of manufacturing the windings; and makes possible the production of a winding, the inductance of which 70 can be determined more accurately than is possible with prior practices. It will be understood that the invention is not to be limited to the illustrated embodiments, but is to be limited only by the scope of the following claims.

75 I claim:

1. The method of making a winding of desired inductance which comprises forming a continuous wire conductor into a sectional winding on a core of insulating material with one section wound upon the core and upon a sheath at least partially surrounding the core, removing the sheath from the core whereby the section initially wound on the sheath can be moved on the core, moving said movable section on the core until the inductance of the entire winding reaches the desired value, and securing said movable section to the core in the adjusted position. 5 10

2. The method of making a winding of desired inductance which comprises winding a continuous wire conductor onto a core of insulating material to form a coil immovable on the core, winding said conductor around the core and a sheath at least partially surrounding the core into the form of a second coil, removing said sheath to permit movement of the second coil on the core, moving the second coil relative to the first coil until the inductance of the entire winding reaches the desired value, and securing the second coil to the core in the adjusted position. 15 20

3. The method of making a winding of desired 25
inductance which comprises winding a continuous
wire conductor onto a core of insulating material
to form coils immovable on the core, winding
said conductor onto the core and a sheath 30
at least partially surrounding the core to form a
final coil, removing the sheath from the core to
permit movement of the final coil on the core,
moving the final coil on the core until the in-
ductance of the entire winding reaches the de-
sired value, and securing the final coil to the core 35
in the adjusted position.

4. The method of making a winding of desired inductance which comprises winding a continuous wire conductor onto a core of insulating material to form self-supporting coils in series-aiding relation immovable on the core, winding said conductor into a final coil movable on said core, said final coil being in series-aiding relation to the immovable coils, the turns of wire in the entire winding being of such number as to cause the winding to have approximately the desired inductance, moving said final coil on the core until the inductance of the entire winding reaches the desired value, and securing the final coil to the core in the adjusted position. 40 45 50

5. The method of making a winding of desired inductance on a core of insulating material which comprises so forming a continuous wire conductor on the core into a sectional multi-self-supporting coil winding that one coil of said winding is movable on the core and the remainder of said winding is fixed to said core, moving said movable coil relative to the fixed part of the winding until the inductance of the entire winding reaches the desired value, and securing said movable coil to said core in the adjusted position. 55 60

6. The method of making a winding of desired inductance on a core of insulating material which comprises so forming a continuous wire conductor on the core into a series-aiding sectional multi-self-supporting coil winding that one coil of said winding is movable on the core and the remainder of said winding is fixed to said core, the turns of wire in the entire winding being of such number as to cause the winding to have approximately the desired inductance, moving said movable coil relative to the fixed part of the winding until the inductance of the entire wind- 70 75

ing reaches the desired value, and securing said movable coil to said core in the adjusted position.

7. The method of making a winding of desired inductance on a core of insulating material which comprises winding a continuous wire conductor onto the core to form a self-supporting coil fixed to the core, winding the conductor onto the core to form a second self-supporting coil in series-
10 aiding relation to said first coil, said second coil being movable relative to the first coil, moving the second coil on the core until the inductance of the two coils reaches the desired value, and securing the movable coil to the core in the ad-
15 justed position.

8. The method of making a winding of desired inductance which comprises forming a continuous wire conductor into a sectional winding on a core of insulating material with a movable section wound upon the core and upon a sheath at least partially surrounding the core, the turns of wire in the entire winding being of such number as to cause the winding to have approximately the desired inductance, moving said movable section on the core until the inductance of the entire winding reaches the desired value, and securing said movable section to the core in the adjusted position. 10
